STABILIZED MULTIVIBRATOR

David E. Kenyon, Smithtown, N. Y., assignor to
 The Sperry Corporation, a corporation of Delaware

Application January 6, 1943, Serial No. 471,518

9 Claims. (Cl. 250—36)

1

My invention relates to circuits for electric discharge devices and concerns particularly relaxation oscillators.

It is an object of my invention to provide stabilized oscillators, the operation and frequency output of which are substantially unaffected by variations in supply voltage, load impedance, anode voltage swing, or tube characteristics.

It is also an object of my invention to provide improved multi-vibrator circuits.

Other and further objects and advantages will become apparent as the description proceeds.

In carrying out my invention in its preferred form, I provide a pair of electric discharge devices which may take the form of triode vacuum tubes with conventional capacitance-resistance cross-coupling between the anode of each tube and the control electrode or grid of the other tube. However, I provide a variable bias for the control electrode of each tube, the magnitude of which is controlled by the circuit of the other tube. In this way, I cause the voltage available for discharging the coupling condenser to vary in proportion to the extent the control electrode voltage is driven negative during each oscillation. By maintaining a fixed ratio between these two magnitudes, I produce constancy in the time duration that each tube is maintained non-conducting and thus stabilize the multi-vibrator circuit by producing constancy of its frequency of oscillation.

In one form of circuit illustrated in the drawings, I provide rectifiers coupled to the anode of one tube for supplying the control electrode bias for the other tube. In another form of my invention, as illustrated, I provide cathode resistors in the circuit of one tube for providing control electrode bias for the other tube.

A better understanding of my invention will be afforded by the following detailed description considered in connection with the accompanying drawings, and those features which are believed to be novel and patentable will be pointed out in the claims appendant thereto.

In the drawings,

Fig. 1 is a circuit diagram of one embodiment of my invention employing rectifiers for providing bias,

Fig. 2 is a circuit diagram of another embodiment of my invention in which cathode resistors are employed for providing variable bias, and

Fig. 3 is a graph explanatory of the principle of operation of the apparatus.

Like reference characters are used throughout the drawings to indicate like parts.

Generally speaking, the frequency of opera-

2

tion of multi-vibrators is determined not only by the time constants of the control electrode circuits of the discharge devices employed, but also by the magnitude of the voltage supply source, the load impedance, the characteristics of the discharge devices, and the anode voltage swing, since these factors affect the discharging rate of the grid condensers, the shape of the discharge curve and the depth to which the grid potential is driven. In order to stabilize the oscillation and make the frequency independent of the factors mentioned, I arrange the control electrode circuits so that the effects of variations in anode voltage swing are compensated. For example, I employ variable bias which varies with anode voltage swing.

In the arrangement illustrated in Fig. 1, variable bias is provided by asymmetrical elements, shown as rectifiers, coupled to the anodes of the discharge devices, as will be explained more in detail hereinafter. The apparatus illustrated in Fig. 1 comprises a pair of electric discharge devices 11 and 12, each having anodes 13 and 14, control electrodes or grids 15 and 16, and cathodes 17 and 18, respectively. The control electrode 15 is cross-coupled by a coupling condenser 19 to the anode 14, and similarly, the control electrode 16 is cross-coupled by a condenser 20 to the anode 13. Grid resistors 21 and 22 are provided. The grid resistors, however, are not connected to a point of fixed potential but to separate, variable-voltage bias sources. The bias voltage source for the control electrode 15 comprises a rectifier 23 coupled to the anode 14, and the bias source for the control electrode 16 of the discharge device 12 comprises a rectifier 24 coupled to the anode 13 of the opposite discharge device 11. The rectifiers 23 and 24 may, if desired, be electric discharge devices of the diode type.

The discharge devices 11 and 12 may be triode vacuum tubes as shown and described, and the rectifiers 23 and 24 may be diode vacuum tubes, but it will be understood that my invention is not limited thereto.

As in conventional multi-vibrator circuits, each of the tubes 11 and 12 is provided with load impedance, represented by the anode resistors 25 and 26. A pair of voltage supply terminals 27 and 28 is provided which may be connected to the positive and negative sides, respectively, of a voltage source, such as a "B" battery 29, the negative side of which may be grounded. In the arrangement illustrated in Fig. 1 the cathodes 17 and 18 are directly connected to the negative supply terminal 28, and the resistors 25 and 26 are connected in series with the anodes 13 and

14, respectively, to the positive supply terminal 27.

In order to supply direct-current or uni-directional bias voltages proportional to the alternating potentials of the anodes 13 and 14, respectively, coupling condensers 31 and 32 are interposed between the anode 14 of the device 12 and the rectifier 23, and between the anode 13 and the rectifier 24. For supplying positive bias voltage as shown and described, the rectifiers 23 and 24 are so connected that their cathodes serve as the output terminals to which the grid leak resistors 21 and 22 are connected. The rectifier anodes are connected to the coupling condensers 31 and 32. Filter circuits comprising resistors 33 and 34 and condensers 35 and 36, respectively, may also be provided. The time constant of the elements 32 and 34 is preferably large in comparison with that of elements 22 and 20. The time constant of elements 31 and 33 is likewise preferably large compared with that of elements 21 and 19. Furthermore, the condensers 35 and 36 should have large capacitances compared with condensers 19 and 20, respectively.

In the arrangement thus far illustrated and described, the condensers 35 and 36 are charged to the peak value of the alternating voltages of the anodes 14 and 13, respectively, that is, the condensers are charged to voltages which are half the respective anode voltage swings. If desired, however, the arrangement may be modified so that each condenser is charged to twice the peak alternating voltage or the complete anode voltage swing. For example, the resistors 33 and 34 may be replaced by two additional rectifiers 23A and 24A, respectively. This connection may be accomplished in Fig. 1 by providing change-over switches S₁ and S₂ with switch blades, which when thrown in the upward position respectively connect the anode of the rectifier 23 to the cathode of rectifier 23A and the anode of the rectifier 24 to the cathode of the rectifier 24A. The rectifiers 23A and 24A have their anodes grounded.

When the switches S₁ and S₂ are transferred from the position illustrated to the upward position, so that the rectifiers 23A and 24A are connected, the rectifier circuits together with the coupling condensers 31 and 32 act as voltage doublers. The rectifiers 23A and 24A prevent the anodes of the rectifiers 23 and 24 from falling below ground potential. Consequently, the condensers 31 and 32 are charged whenever the potentials of the anodes 13 and 14 fall, and the charges accumulated during the negative half cycles of anode voltage pass through the rectifiers 23 and 24 to the condensers 35 and 36 during the positive half cycles of anode voltage at the anodes 13 and 14. The result is that the condensers 35 and 36 are progressively charged with higher and higher potentials, until the condenser 35 has reached a potential equalling the voltage swing of the anode 14 and the condenser 36 has reached a potential equalling the voltage swing of the anode 13. The condensers 31, 32, 35 and 36 are relatively large so that no appreciable variation in the accumulated charge takes place so long as there is no change in the voltage swing of the anodes 13 and 14. Consequently, the cathodes of the rectifiers 23 and 24 serve as bias points for the control electrodes 15 and 16. The potentials of the control electrodes 15 and 16 tend to return to the potentials of the cathodes of the rectifiers 23 and 24, respectively.

It will be understood that in multi-vibrator

circuits the discharge devices become alternately conducting (or in some cases maximum conductivity is alternately transferred from one device to the other). As each device becomes conducting (in the type of multi-vibrator assumed) the coupling between its anode and the control electrode of the other device results in the control electrode of the latter device being driven sharply negative past cut-off, causing the latter device to become non-conducting as the first device becomes conducting. As the coupling condenser discharges, however, the control electrode of the device which has been non-conducting gradually rises to cut-off, causing the latter device to become conducting and to drive the control electrode of the first device negative beyond cut-off. Thus, each discharge device tends to approach a quiescent condition in which it is conducting, but in so doing it extinguishes the current flow in the other device. If the control electrodes are biased to ground potential or to some other fixed potential the time required for the coupling condenser to discharge sufficiently to permit the control electrode to rise to cut-off is varied by various factors and these factors, therefore, influence the non-conducting period of the discharge device and the oscillation frequency of the circuit. The charge collected by the coupling condenser depends upon the magnitude of the supply voltage source 29 and the extent to which the control electrode is driven negative depends upon the voltage swing of the anode of the other device, which, in turn, depends upon the load impedance and the characteristic curve of the discharge device. For a given load resistance the anode voltage swing depends upon the anode-cathode current or discharge current of the device. The effect of these factors is overcome in accordance with my invention because the control electrodes are separately biased by connecting them to bias points the potentials of which vary to compensate for variations in the anode voltage swing of the discharge device which controls the control electrode of the other device.

Assuming that at the instant of initial consideration, the discharge device 11 is conducting and the discharge device 12 is non-conducting, the coupling condenser 19 will become charged by the supply voltage of source 29 since the anode 14 is at the potential of the positive supply terminal 27 and the control electrode 15 is substantially at zero or ground potential. Owing to the characteristics of the discharge devices 11 and 12, the control electrode potential cannot rise above zero. The potential of the cathode of the rectifier 23 is at a value E₁, which is the value of the anode voltage swing of the anode 14. Current tends to flow in the grid leak resistor 21, but for the reason just stated, the control electrode 15 remains at zero or ground potential. At some later instant, when the potential of the control electrode 16 has risen to cut-off, the discharge device 12 becomes conducting abruptly, its anode voltage falls abruptly by reason of the flow of current in the load impedance 26, and the potential of the control electrode 15 is driven sharply negative. The value of the negative potential to which the control electrode 15 is instantaneously driven is represented as E₂. In Fig. 3 the bias potential provided by the condenser 35 is represented as E₁ and the negative anode voltage swing, through which the control electrode 15 has been driven, is represented by E₂. The voltage change acting in the discharge

circuit of the condenser 19 is therefore the voltage $E_1 + E_2$ and the condenser 19 tends to discharge along a curve 27 (Fig. 3) which is asymptotic to the value of E_1 . The reason for this will be apparent from a consideration of the nature of the condenser discharge.

The discharge curve of a condenser representing the change in voltage across the plates produced by a disturbance changing the voltages acting in the discharge circuit of the condenser is determined by the difference between the voltages in the discharge circuit before and after the disturbance. In the case of the coupling condenser 19, this change in voltage is the sum of the bias voltage provided by the condenser 35, represented by the symbol E_1 , and the anode voltage swing of the discharge device 12, represented by the symbol E_2 . In Fig. 3 the potential of the control electrode 15 with respect to ground is represented by the discharge curve 37, which is drawn with voltage measured in the vertical direction and time in the horizontal direction. While the discharge device 11 is still conducting, the potential of its control electrode is fixed at zero, because electron flow in the device 11 would prevent its control electrode from becoming positive, and the bias potential E_1 provided by the rectifier 23 and the condenser 35 has no effect on the condenser 19. Then at the instant the device 12 becomes conducting the potential of the control electrode is driven negative through the voltage E_2 . The control electrode is now free to float at the potential determined by the coupling condenser charge. One plate of the condenser 19 is now effectively connected through the grid leak 24 to the cathode of the rectifier 23 which is at E_1 volts; the other plate, connected to the anode 14 of the device 12, must fall E_2 volts. The total change in voltage acting in the condenser discharge circuit is therefore $E_1 + E_2$, and the discharge curve 37 is asymptotic to the line E_1 in Fig. 3. For convenience, the difference between zero potential and the actual cut-off potential of the control electrode is disregarded since the negative voltage swing is made very large in comparison with the actual cut-off voltage.

The time required for the potential of the control electrode 15 to rise to the value zero, represented in Fig. 3 by the symbol t , determines the time that the discharge device 11 remains non-conductive. If the circuit conditions should be changed by reason of a change in voltage supply, in the impedance of the load impedance 26, or in the characteristics of the device 12, E_1 and E_2 will change in the same proportion since they have been made equal. The discharge curve 37 will become more or less steep than is illustrated in Fig. 3. However, the time duration t will remain unchanged. Since the curve 37 is exponential, the time required for the ordinate to rise to a fixed proportion of the total change is constant even though the total change in voltage may be varied. Consequently, the non-conducting period of the discharge device 11 is stabilized and is independent of the various factors mentioned which vary with changes in circuit conditions. In a similar manner, the non-conducting period of the discharge device 12 is stabilized and the frequency of the multivibrator circuit is stabilized. Within reasonable limits, I have even found it possible to replace one pair of electric discharge devices 11 and 12 of a given type and make by another pair of somewhat different type and make without causing variation in the frequency of the multi-vibrator circuit.

In the operation as explained, it was assumed that the bias potential E_1 was equal to the negative swing E_2 of the control electrode. However, the same stability would be obtained if some other fixed ratio were maintained between the value E_1 and the value E_2 , equality of the two values not being necessary. For example, if the switches S_1 and S_2 are moved to the downward positions, the condensers 35 and 36 will be charged to potentials respectively equaling the peak alternating voltages of the anodes 14 and 13 or one-half the anode voltage swings. Nevertheless, a fixed proportion is maintained between the magnitudes of the voltages E_1 and E_2 , discussed in connection with Fig. 3, and stability of oscillation is obtained. If desired, the circuit may be modified to maintain any other convenient ratio between the bias potential of each discharge device and the voltage swing of the anode of the other discharge device.

In the arrangement of Fig. 1, with the switches S_1 and S_2 in the downward positions, the potentials of the condensers 35 and 36 may continuously equal one-half the respective anode voltage swings precisely only if it is assumed that the resistors 33 and 34 are large in relation to the resistors 25 and 26 respectively, and that the grid leak resistors 21 and 22, in turn, are large in relation to the resistors 25 and 26. However, these assumed resistance relationships are not necessary to the satisfactory operation of the circuit. For maximum stability, nevertheless, I prefer to utilize resistance relationships substantially as assumed.

As pointed out, the control electrodes 15 and 16 are provided with positive biases which are equal to a substantially constant fraction of the anode voltage swings of the opposite tubes and which compensate for variations in swing which may be produced by variations in the voltage of the supply source 29, variations in the load impedances 25 and 26, or variations in tube characteristics. Each tube stage forms a portion of a control circuit for the other so that I may stabilize each stage by compensating variation in the other.

In place of using separate rectifiers for supplying the bias voltages, I may modify the circuits of the main tubes 11 and 12 so that each will provide a bias voltage for the control electrode of the other tube. For example, as illustrated in Fig. 2, the tubes 11 and 12 are provided with cathode resistors 39 and 40, respectively, connected between the cathodes 17 and 18, and the negative supply terminal 28. The grid resistor 21 is connected between the control electrode 15 and the cathode 18 of the other tube 12, and likewise, the grid resistor 22 is connected between the control electrode 16 and cathode 17.

In this case the control electrode of each discharge device is biased to the potential of the cathode of the opposite discharge device when the latter is conducting. Considering the coupling condenser 19, and referring to Fig. 3, E_1 is the voltage across the resistor 40 when the device 12 is conducting. As before, E_2 is the anode voltage swing of the device 12. E_1 and E_2 are both proportional to the anode-cathode current or discharge current of the electric discharge device 12. Assuming constant ratio of the resistances of the elements 26 and 40, the ratio of E_1 to E_2 remains constant and the oscillator is stable in frequency. Variations in load impedance have some effect, but other changes in circuit conditions do not vary the oscillator frequency.

For improving the wave from the voltages and

currents appearing in the tubes in the circuit of Fig. 2, by-pass condensers 41 and 42 may be connected across the cathode resistors 39 and 40, respectively. I have found that stability is obtained with or without such by-pass condensers.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A stabilized multivibrator, comprising a pair of electric discharge devices each having an anode, a cathode, and a control electrode, first and second supply terminals for connection to a current source, a pair of load impedances connected between the first supply terminal and the respective anodes, coupling condensers connected between the anode of one discharge device and the control electrode of the other, grid leak resistors connected between the control electrode of one discharge device and the cathode of the other, and cathode resistors connected between the respective cathodes and the second supply terminal.

2. Apparatus such as set forth in claim 1, having by-pass condensers connected across each of the cathode resistors.

3. A stabilized multivibrator, comprising a pair of electric discharge devices each having an anode, a cathode, and a control electrode; first and second supply terminals for connection to a current source; a pair of load impedances connected between the first supply terminal and the respective anodes; cross-couplings between the anode of one device and the control electrode of the other; and a variable-voltage bias-supply source connected to each of said control electrodes, each bias-supply source comprising a rectifier coupled to the anode of the opposite discharge device.

4. A stabilized multivibrator comprising first and second electric discharge devices each having a cathode, an anode, and a control electrode; first and second impedances respectively connecting the cathodes of said devices to a junction point; means including third and fourth impedances for supplying the respective anodes of said devices with positive potentials relative to said junction point; fifth and sixth impedances coupling the control electrode of said first device respectively to the anode and to the cathode of said second device; and seventh and eighth impedances coupling the control electrode of said second device respectively to the anode and to the cathode of said first device.

5. A stabilized multivibrator comprising first and second electric discharge devices each having a cathode, an anode, and a control electrode; first and second impedances respectively connecting the cathodes of said devices to a junction point; means including third and fourth impedances for supplying the respective anodes of said devices with positive potentials relative to said junction point; fifth and sixth impedances coupling the control electrode of said first device respectively to the anode and to the cathode of said second device; and a seventh impedance coupling the control electrode of said second device to the anode of said first device.

6. A stabilized multivibrator comprising first and second electric discharge devices each having a cathode, an anode, and a control elec-

trode; first and second impedances respectively connecting the cathodes of said devices to a junction point; means including third and fourth impedances for supplying the respective anodes of said devices with positive potentials relative to said junction point; fifth and sixth impedances connected in series between the anode and cathode of said first device, the junction thereof being coupled to the control electrode of said second device; and seventh and eighth impedances connected in series between the anode and cathode of said second device, the junction thereof being coupled to the control electrode of said first device.

7. A stabilized oscillation generator of the multivibrator type for producing a signal having a given period, comprising a pair of electric discharge devices each having an anode, a cathode and a control electrode; first and second supply terminals for connection to a current source; a pair of load impedances connected between the first supply terminal and the respective anodes; cross-couplings between the anode of each device and the control electrode of the other, said cross-couplings having time constants short relative to said period; a direct-current bias-producing means associated with each of said devices for providing a voltage dependent upon the average amplitude of anode voltage and current variations in the device but substantially independent of cyclical variations thereof; and electrically conductive impedance means connecting the direct-current bias-providing means associated with each device to the control electrode of the other device.

8. A stabilized oscillation generator of the multivibrator type for producing a signal having a given period, comprising first and second electric discharge devices each having a cathode, an anode and a control electrode; first and second supply terminals for connection to a current source; a pair of load impedances connected between the first supply terminal and the respective anodes; a cross-coupling between the anode of the first device and the control electrode of the second device and a cross-coupling between the anode of the second device and the control electrode of the first device, said cross-couplings having time constants short relative to said period; direct-voltage storage means connected to the first device for producing a direct voltage dependent on the average amplitude of current variations in said first device but substantially independent of cyclical variations thereof; electrically conductive impedance means coupling said storage means to the control electrode of said second device; further direct-voltage storage means connected to the second device for producing a direct voltage dependent on the average amplitude of current variations in said second device but substantially independent of cyclical variations thereof; and further electrically conductive impedance means coupling said further storage means to the control electrode of said first device.

9. A stabilized multivibrator comprising first and second electric discharge devices each having a cathode, an anode, and a control electrode; a pair of load impedances connected respectively between said anodes and the positive terminal of a source of potential; means for applying to each of said control electrodes a unidirectional potential having a magnitude dependent upon the average amplitude of the current flowing in the circuit of the opposite anode; and separate

means for applying to each of said control electrodes a potential dependent upon the voltage fluctuations at the opposite anode.
